UNITED STATES PATENT OFFICE.

JOHN S. VANEK, OF OKLAHOMA CITY, OKLAHOMA.

SHORT-BARRELED PEN AND PENCIL HOLDER FOR SECOND FINGER.

Application filed February 23, 1926. Serial No. 89,876.

My invention relates to improvements in short barreled pen and pencil holder for fitting on the second finger.

The object of the invention is to produce a device of the character described, which will readily fit and be adapted to be used on the second finger of the hand; easily operated; work easily and without causing a tension, or cramping, or pen paralysis; easily and cheaply manufactured, installed and applied; efficient in writing.

Other objects and novel features and application of the invention will appear in the following specifications, claim, and drawing, in which drawing,

Figure 1 is an elevational view of the device as attached to the second finger of the right hand. Figure 2 is a perspective view of the device.

Like characters of reference designate like parts in all the figures.

In the ordinary method of holding a pencil or pen in writing wherein it is held tightly between the ends of the thumb and first or index finger and near the first joint of the second finger resting the middle portion of the barrel of the pen or pencil against the upper portion of the index finger near the knuckle, and balancing the hand on the outside of the fourth or little finger and the third finger, and on the right side of the forearm, the hand, fingers and arm assume a somewhat cramped position, so that continuous use in that way tends to tire, and many times to cramp the members so used, and at times causes what is known as pen-paralysis. Those who have tried my manner of using my method of fastening the pen or pencil on the second finger, and especially those who have been unfortunate enough to lose their index finger, find the position of holding the hand and forearm in such use is much more natural than the use of the present system of holding the pen or pencil; and that they can write naturally for long periods of time without fatigue or cramps, and never suffer with pen-paralysis.

The device consists of a double looped spring wire member, the outer end corners of which are shown at 1, 2, the inner end corners at 4, 5; these two looped members are made integral and are joined together at 3; fastened to the inner end of said wire member at 6^a is shown a partially closed ferrule member the inside of which is shown at 6, the outer corner portions nearest the

fastening to said wire member are shown at 7, 8; the outer edges of said ferrule member are on straight lines from 7 to 7^a and 8 to 8^a, at which points there are two cut in slot portions 9, 10, which are between the last described portion of said ferrule member and a second portion of the same, the latter being more extended than said first portion, the corners and edges of which more extended portion are shown at 11, 13, and 12, 14. Said second portion of said ferrule member at 11, 13 and 12, 14 snugly fits around the pen or pencil 15 and said first described portion of said ferrule member holds in the inner portion 6 the pencil stock, or the lower part of the short barreled pen 18. The short barrel of the pen for the fountain pen variety, if desired, is shown at 17, 18, 19, and the aperture therein for filling is shown at 20 closed by a top 22 screw threaded at 21 to fit in said like screw threaded aperture 20, opening into the inside barrel portion 20^a. The fingers of the right hand are shown: the thumb at 23, the first, or index finger, 24, the second finger at 25, the third or next to the little finger at 26, and the fourth or little finger at 27.

In operation the second finger 25 is inserted in the opening between 1 and 2 and over the fastened portion 3 then through the opening between 4 and 5 under the ferrule member, after being thus installed the hand is naturally laid down on the table, or desk, and the thereby extending of the second finger 25 tightens the wire member holding the short barreled pen, or short pencil tight on the second finger member 25 at 28 and 29 the portion of the short barreled pen, or short pencil at 31 contacting the portion of the second finger at 28 and portion 30 thereof contacting the portion of the second finger shown at 29, thereby securely holding the short pencil or short barreled pen in writing position so as to make the point of the pencil 16 or the pen point 16 (not claimed as a part of this patent, per se,) contact the writing surface.

From the description and the accompanying one page drawing, and the specifications, the advantages of construction, application and manufacture will be apparent to those skilled in the art to which my invention pertains. I have entered into a detailed description of the construction and relative arrangement of the parts embraced in the present and preferred embodiment of my in-

vention in order to impart a full, clear and exact understanding of the said embodiment. I do not desire, however, to be understood as confining myself to the specific construction and relative arrangement of parts inasmuch as in the future practice of the invention various changes and modifications may be made such as fall within the scope of my invention as defined in my appended claim.

10 Having thus described the invention, what is claimed and desired to be secured by Letters Patent, is:

15 A device of the character described, comprising a resilient wire member having an upper and lower loop medially fastened together, the outer end of said upper loop be-

ing adapted to fit on top of the third joint of the second finger of the writing hand, the outer end of said lower loop being adapted to fit on top of the first joint of said finger, 20 the medial fastening being adapted to movably fit centrally under said second finger, the whole being adapted to movably tighten and loosen on said finger on its being bent or straightened; an open topped resilient 25 ferrule member rigidly fastened at its upper periphery to the outer end of said lower loop at an angle, and being adapted to securely hold for writing purposes writing utensils.
